CARD INDEX

Raymond Edward Bauder, Chicago, Ill.

Application February 8, 1943, Serial No. 475,119

6 Claims. (Cl. 129—16.7)

The invention relates to card index and similar systems of the general type in which the cards are provided at their upper rear portions with one or more downwardly projecting tongues to be hooked upon subjacent cards in a filing tray, said cards having lateral ears for reception in guide grooves along the edges of the tray.

The invention aims primarily to provide a new improved card construction in which novel provision is made for reinforcing the upper portion of the card, giving a two-ply construction to the lateral ears, and insuring such positioning of the tongue or tongues that it or they will readily hook upon the subjacent card.

Further objects are to provide for holding a marker, sheet, auxiliary card or the like against said body portion of the card by means of one or more of the tongues; to provide a novel connection between a main card and an auxiliary card which will permit said auxiliary card to be shifted to a position projecting beyond said main card for any desired special purpose; to provide a novel double-card form of the invention; to provide for connecting duplicate cards with each other; to provide a card which may be quickly and easily placed in or removed from the filing tray and one which may be readily placed in a typewriter, and to provide a simple and inexpensive, yet a durable and very desirable construction.

With the foregoing and minor objects in view, the invention resides in the novel subject matter hereinafter described and claimed, description being accomplished by reference to the accompanying drawings.

A number of forms of construction have been illustrated in the drawings and the views have been grouped and bracketed, and identified as "Form 1," "Form 2," etc., to facilitate consideration.

Figure 1 is a front elevation partly broken away and in section showing a plurality of the cards constructed in accordance with "Form 1," engaged with a filing tray.

Fig. 2 is an enlarged fragmentary section on line 2—2 of Fig. 1.

Fig. 3 is a transverse section on line 3—3 of Fig. 1.

Fig. 4 is a fragmentary perspective of the upper left corner of one of the cards.

Fig. 5 is a broken away view illustrating the upper portion of one of the cards, before it is folded.

Fig. 6 is a fragmentary front elevation show-

ing a main and an auxiliary card connected in accordance with "Form 2."

Fig. 7 is a fragmentary rear elevation.

Fig. 8 is a fragmentary longitudinal section showing the auxiliary card shifted to a position in which it projects beyond the main card.

Fig. 9 is an enlarged sectional view on line 9—9 of Fig. 6.

Figs. 10 and 11 are respectively fragmentary front and rear perspectives showing "Form 3."

Figs. 12 and 13 are similar perspectives relating to "Form 4" and Fig. 14 is a detail section on line 14—14 of Fig. 13.

Figs. 15 and 16 are fragmentary front perspectives showing "Forms 5 and 6" respectively.

Figs. 17 and 18 are fragmentary rear elevations showing "Forms 7 and 8" respectively.

Fig. 19 is a front elevation and Fig. 20 a section on line 20—20 of Fig. 19 showing "Form 9."

Figs. 21 and 22 are similar views showing "Form 10," Fig. 22 being a section on line 22—22 of Fig. 21.

Figs. 23 and 24 are respectively a front elevation and a detail section relating to "Form 11," Fig. 24 being taken on line 24—24 of Fig. 23.

Figs. 25 and 26 are respectively front and rear fragmentary perspectives of the form of construction identified as "Form 12," this being a double-card form of the invention.

Figs. 27 and 28 are similar views relating to "Form 13," and Fig. 29 is a detail section on line 29—29 of Fig. 28.

All forms of the invention possess certain features in common, and these features will be given the same reference characters in all forms of construction, the ways in which the various forms differ from each other being explained after a general or generic description.

The card 1 is of substantially rectangular form and may be constructed from ordinary cardboard or any other desired material. The upper corners of the card 1 are each provided with an integral lug 2 (Fig. 5), and these lugs project laterally beyond the vertical edges of the card.

The upper portion of the card and its lugs 2 are forwardly folded upon themselves, providing the card with a head bar 3 and with two-ply lateral ears 4 at the ends of said head bar. The body portion of the card 1 is formed with one or more slots 5 (each of which may be a mere slit if desired), each slot being located at the lower edge of the head bar 3. A tongue 6, formed integrally with the lower edge of the head bar 3, is associated with each slot 5, each tongue extending rearwardly through its respective slot 5 and project-

55

ing downwardly in diverging relation with the aforesaid body portion of the card 1.

The head bar 3 reinforces the upper end of the card 1 and provides for giving the lateral ears 4 a reinforced two-ply construction. Then too, as the tongue or tongues 6 is/are carried by said head bar, the attached upper end of each tongue is in a plane above the card 1, insuring that each tongue after passage through its respective slot 5, shall occupy the proper diverging relation with the card. Thus, the tongue or tongues of one card may readily hook upon a subjacent card as shown in Fig. 2, when a plurality of the cards are placed in a suitable filing tray. Such a tray has been illustrated at 7 in Figs. 1, 2 and 3, the side walls 8 of said tray being formed with longitudinal grooves 9 in their inner sides to receive the ears 4. It is preferable that the bottom or rear wall of the tray be formed with longitudinal grooves 10 to receive the tongues 6 (or with only one groove for single-tongue cards). The cards may be easily placed in the tray, simply by upwardly bowing them enough to permit insertion of the ears 4, and any inserted card may be downwardly slid to cause its tongue or tongues 6 to hook upon the reinforced upper edge portion of the subjacent card. The cards may also be removed with equal facility by reversal of these operations and any card may be readily placed in a typewriter when it is desired to write any desired data upon it. When a number of the cards are hooked together in the tray, their lower ends are exposed as seen in Fig. 1, and said ends may carry any desired identifications. Guide lines for use if such identifications are to be manually written, are indicated at 11, and at 12 I have indicated a hinge line upon which the body portion of the card may be upwardly swung with respect to its reinforced upper portion, said hinge line being adjacent the lower edge of the head bar 3. The hinge line 12 may be about even with one edge or the other of the slot or slots 5 or may be in alignment with said slot or slots. Moreover, each slot may be so narrow as to be a mere slit if desired.

In Figs. 6 to 9 ("Form 2"), an auxiliary card 13 lies upon the card 1, is inserted under the head bar 3 and is formed with a slot 14 through which the tongue 6 extends, said slot being sufficiently long to permit the card 13 to be shifted upon the card 1 until it projects beyond said card 1 as seen in Fig. 8, said slot 14 being preferably of a length to allow such shifting of said card 13 either to the right or left. When shifted to a projected position, the card 13 acts as an indicator, for example, to show an account being posted, or the shifted card may serve as a marker for any other special purpose. To prevent the upper corners of card 13 from striking the guide flanges of the filing tray when said card 13 is shifted and to allow the projected end of said card to overlie the adjacent one of said flanges, said corners are notched at 13'. While card 13 is shown associated with a card 1 having a single tongue 6 and slot 5, it is obvious that this same general association may be carried out with a plural tongue and slot construction.

The construction shown in Figs. 10 and 11 ("Form 3") is practically identical with that shown in Figs. 1 to 5 ("Form 1") but the lower edge of the head bar 3 is formed with short vertical slits 15 at the edges of the tongues 6. This permits passage of the tongue through the slot 5 with less abrupt bending and lessens the binding of the lower edge of said slot upon the tongue 75

when the body portion of the card is being swung upwardly.

"Form 4" shown in Figs. 12, 13 and 14 is very similar to "Form 1," but in forming the hinge line 12, a creasing operation is performed which offsets the body portion of the card 1 forwardly to some extent from its reinforced head portion, thus permitting the cards to nest more compactly.

Fig. 15 ("Form 5") illustrates the fact that the head bar 3 may be relatively narrow and may have its lower edge spaced upwardly from the lower extremity of the ear 4 if desired, and Fig. 16 ("Form 6") discloses an unusually wide head bar 3. As the lower edge of this head bar locates the tongues 6 and these tongues control the spacing of the cards lengthwise of the tray, a wide head bar will insure projection of any card quite a distance down beyond the next overlying card, whereas such downward projection will be less with a relatively narrow head bar. In Fig. 15, I have also illustrated slits 16 along the line upon which the head bar 3 is downwardly folded, which is of particular advantage with relatively thick cards which might otherwise have a tendency to break along the fold line.

In Fig. 17 ("Form 7") and Fig. 18 ("Form 8"), the tongues 6 have their edges disposed in downwardly converging relation from their upper to their lower ends, said edges being more acute to each other in Fig. 17 than in Fig. 18. When the tongues are comparatively wide as seen in Fig. 18, two to a card may be used, whereas otherwise, three may be required. A single tongue similar to that shown in Fig. 18 but wider (as in "Form 2") could also be used if desired.

In Figs. 19 and 20 ("Form 9"), a marker 17 of cardboard, Celluloid or other desired material, lies upon the front of the card 1 and has its upper end inserted beneath the head bar 3, said marker having a slot 18 through which one of the tongues 6 extends, whereby said marker is effectively attached to the card with its lower end conspicuously displayed for one reason or another.

In Figs. 21 and 22 ("Form 10"), a memorandum sheet or the like 19, another sheet 19, and a card 20 are attached to the card 1 by passing the tongues 6 through slots 21 in said sheets and card 18, 19 and 20, the upper ends of said sheets and card being inserted under the head bar 3. If desired, one of the sheets or the card, for example, sheet 19, may have pockets 22 at its lower corners into which the lower corners of cards, slips of paper or the like may be inserted.

In Fig. 23 ("Form 11"), let it be assumed that the card 1 is formed from Celluloid or similar transparent material, which is preferable in this case. Along the lower edge of the card, an upwardly open pocket 23 is provided to receive the lower end of another card or the like 24 to be mounted upon the body portion of the card 1. Inclined slits 25 are formed in card 1, through which to insert the upper corners of card 24.

Figs. 25 and 26 ("Form 12") disclose a double-card form of the invention, in which a second card 26 has its upper end integrally joined to the lower edge of the head bar 3, the line of juncture between the two being formed with a plurality of slits 27 which constitute a hinge line upon which card 26 may be upwardly swung from card 1. In this form of construction, the hinge line 12 for the body portion of the card 1 is also preferably slotted as seen in Fig. 26, and the fold line along which the head bar 3 is downwardly folded, may be similarly perforated as indicated at 28.

In Figs. 27, 28 and 29 ("Form 13"), two dupli-

cate double-cards are nested one within the other and are connected with each other by passing the tongues 6 of the inner card not only through the slots 5 of said card, but through the slots 5 of the outer card. The tongues 6 of this outer card remain in the plane of the card portion from which they are stamped until the two cards are to be later detached, and said outer card arranged for its tongues to hook upon another card in the filing tray.

From the foregoing taken in connection with the accompanying drawings, it will be seen that novel and advantageous provision has been made for carrying out the objects of the invention. While preferred details of construction have been illustrated and a number of variations have been disclosed, attention is invited to the fact that still further modifications could well be made within the scope of the invention as claimed.

I claim:

1. A substantially rectangular card, the upper corners of said card each having an integral lug, said lugs projecting outwardly from the vertical edges of the card, the upper edge portion of said card and said lugs being folded forwardly upon themselves, providing the card with a reinforcing head bar and with projecting two-ply ears at the ends of said head bar, said head bar having at least one integral tongue extending downwardly and rearwardly, said card having at least one slot through which said tongue extends to hook upon a subjacent card.

2. A structure as specified in claim 1; together with a flat member lying upon said card, inserted under said head bar and having a slot through which said tongue extends.

35

3. A structure as specified in claim 1; together with a flat member lying upon said card, inserted under said head bar and having a slot through which said tongue extends, said slot being sufficiently long to permit shifting of said flat member to a position in which one of its ends projects beyond one of the ear-carrying ends of said card.

4. A structure as specified in claim 1; together with a flat member lying upon said card, inserted under said head bar and having a slot through which said tongue extends, said slot being sufficiently long to permit shifting of said member to a position in which one of its ends projects beyond one of the ear-carrying ends of said card, said end of said flat member having a notch in its upper corner for the purpose set forth.

5. A structure as specified in claim 1; together with a second card integrally joined at its upper edge to the lower edge of said head bar and lying upon the first mentioned card.

6. A substantially rectangular card, the upper corners of said card each having an integral lug, said lugs projecting outwardly from the vertical edges of the card, the upper edge portion of said card and said lugs being folded forwardly upon themselves, providing the card with a reinforcing head bar and with projecting two-ply ears at the ends of said head bar, the body portion of said card having at least one slot at the lower edge of said head bar, said lower edge of said head bar having at least one integral tongue extending rearwardly through said slot and projecting downwardly to hook upon a subjacent card.

RAYMOND EDWARD BAUDER.
